FIRE ALARM SYSTEM

Julius C. Lowry and Ora M. Rybolt,
Detroit, Mich.

Application July 22, 1932, Serial No. 624,076

2 Claims. (Cl. 200—138)

This invention relates to thermally controlled signal apparatus and the principal feature and object of the invention resides in the provision of a thermally controlled device which is enclosed in a housing having a foraminous wall whereby a rise in temperature of the air adjacent the housing will cause the thermally controlled device to move to close an electrical circuit through a signal thereby giving warning of a dangerous rise in temperature of the air adjacent the device.

Another object of the invention resides in the provision of a thermally controlled device which is connected with the circuit of a door bell operated by a push button and which is so connected as to permit normal usage of the push button and which will close the circuit through the door bell to keep the same continuously ringing when the temperature adjacent the thermally controlled device rises above a predetermined point.

Another object of the invention resides in the provision of a thermally controlled device which includes a bimetallic thermally controlled element having one end connected to an electric terminal and the opposite end in spaced relation to a second electric terminal and the element so arranged as to close the circuit through the two terminals when the temperature of the air adjacent the same has risen above a predetermined point.

These objects and the several novel features of the invention are hereinafter more fully described and claimed and the preferred form of construction by which these objects are attained is shown in the accompanying drawing in which—

Fig. 1 is a diagrammatic view showing my thermally controlled device connected to a doorbell circuit.

Fig. 2 is a section through a housing having my improved thermally controlled device positioned therein.

Fig. 3 is a similar view showing a modified form of housing.

Referring to the drawing, the bimetallic thermostatic strip 1 has one end connected to the post 2 while the free end normally extends to a point in spaced relation to the post 3. The posts 2 and 3 are mounted in the base of the cup shaped member 4 and are suitably insulated therefrom. The member 4 is secured to the plate 5 by means of the screws 6 and by referring to Fig. 2 it will be seen that the plate is formed with the louvres 7 so that the thermostat 1 is responsive to changes in temperature of the air adjacent the plate. A housing 8 encases the cup shaped member 4 and is secured thereto by means of the screws 9. It

will be understood that the housing 8 is preferably inserted in a recess in the wall of the room where it is desired to install the device and the plate 5 will cover the recess and will be inconspicuous and decorative in appearance.

The wall of the housing is formed with a pair of apertures 10 and a wire 11 is connected to the post 2 and extends through one of the apertures 10 while the wire 12 is connected to the post 3 and extends through the other aperture 10. The wires 13 and 14 are connected to some source of current supply (not shown) and to the primary winding of the transformer 15. A wire 16 has one end connected to one terminal of the secondary winding of the transformer while the opposite end is connected to the terminal 17 of the door bell 18. A wire 19 is connected to the opposite terminal of the secondary winding while the opposite end is connected to one terminal of the usual push button 20 and the opposite end of the wire 12, to that connected to the post 3, is connected to the opposite terminal of the push button 20. A wire 21 has one end connected to the terminal 22 of the door bell 18 and the opposite end to the wire 12 and the wire 11 leading from the post 2 is connected to the wire 19. It will thus be noted that by pressing the push button 20 that the electrical circuit through the bell 18 will be closed and when pressure is released from the push button the circuit through the bell will be broken in the usual manner.

In the event, however, that the temperature of the air adjacent the housing 8 rises above a predetermined point then the free end of the thermostat 1 will move over and contact the post 3 thereby closing the electrical circuit through the bell 18 and causing the same to continuously ring until the temperature lowers sufficiently to cause the free end of the thermostat 1 to move out of contact with the posts 3 or until the main switch in the building in which the device is installed is opened. It will be understood, of course, that although only one unit has been shown connected with the doorbell circuit that any number of the devices may be connected in a similar manner so that movement of any one of the thermostatic elements will close the circuit through the bell. It will thus be seen that a number of the devices may be installed in a house or building at very little expense so that a dangerous rise in temperature of the air adjacent any one of the devices will give immediate warning to that effect.

Referring to Fig. 3, we have shown a modified form of structure in which the flange of the cup shaped member 4 is secured to the housing 25

preferably by spot welding and it will be noted that the housing 25 is formed with apertures 26 in the base and also in the periphery thereof so that the temperature of the air around the thermostatic 1 is practically the same as that immediately outside of the housing 25.

From the foregoing description it becomes evident that we have provided a simple and inexpensive device that may be connected with a signal 10 whereby an electric circuit through the signal will be closed when the temperature of the air adjacent the signal has risen above a predetermined point.

Having thus fully described our invention, its 15 utility and mode of operation, what we claim and desire to secure by Letters Patent of the United States is—

1. A thermostatic switch comprising a housing 20 adapted to be set in a wall and having an open outer face, a cover plate detachably secured thereto having an opening and a series of spaced 25 elements extending across the opening at an angle to the horizontal to obscure the interior of the housing from view, a thermostatic element, a support therefor attached to the cover plate to position said thermostatic element closely adjacent to the said opening in the plate, a post attached to the support to which an end of the 30 thermostatic element is attached, an electrical contact member carried by the support adjacent to which the opposite end of the thermostatic

element is positioned in normally spaced relation, the terminals of an electric circuit extending into the housing and connected respectively with said post and said contact member whereby through influence of heat the thermostatic member 5 may be actuated to close the circuit across said post and contact member.

2. A thermostatic switch comprising a housing having an open end and adapted for mounting in a wall opening the open end at the face of the 10 wall, a removable plate for covering said open end, said plate having a series of louvers providing spaced bars lying at an angle to the vertical and obscuring the interior of the device to view from the interior of a room, the louvers providing for 15 ingress of atmosphere of the room to the interior of the housing, a pair of posts carried by the said removable plate and providing terminals of an 20 electric circuit, said housing having openings for introduction of the circuit wires thereinto, a bimetallic element carried by the plate and lying closely adjacent the louvers, said element being in the form of a spiral coil attached at its center to one of the posts and the free portion thereof 25 adjacent the other whereby the expansion of the element under an increase in temperature in the air space of the device causes the same to engage said other post and close the electric circuit.
